LEWIS FERRY MOODY, OF PHILADELPHIA, PENNSYLVANIA

HYDRAULIC APPARATUS

Application filed May 28, 1927. Serial No. 195,105.

This invention relates to hydraulic turbines and particularly to those of vertical shaft type.

In the effort to increase the speed of a turbine under a given head so as to permit a reduction in the size of the generator driven by the turbine as well as the size of the turbine itself and the accompanying power house structure, runners having extremely high values of specific speed have been developed, but these necessarily require the location of the runner at a low point with respect to tail water. As hereinafter explained in detail, the higher the specific speed the lower the runner must be placed with respect to tail water, and conversely the higher the runner is placed with respect to tail water, the lower will be its permissible specific speed. With the high specific speed runner located at the required low point there is, in many plants, available space above the runner for the location of a second runner connected with the same shaft which if it could be added to the unit would materially increase the power output and consequently the total specific speed of the entire unit.

The object of my invention is to provide a turbine in which this space above the lower runner contains an auxiliary upper runner mounted on the same shaft with the lower runner and so combined therewith that the lower runner may have a high specific speed while at the same time the auxiliary upper runner is adapted to operate at a lower specific speed suitable for its higher elevation above tailwater. The fact that runners of different specific speed are adapted to operate normally at the same actual speed permits the two runners to be mounted on the same shaft. In this way the high specific speed of the lower runner is maintained, and at the same time additional power is efficiently generated and delivered to the shaft by the lower specific speed upper runner, thus increasing the specific speed of the turbine unit as a whole.

The double runner turbines of the prior art are unable to operate most efficiently because there is mounted on the same shaft at least two substantially identical runners

which are therefore suited only for the same elevation and specific speed. For reasons which will be apparent hereinafter these prior runners are designed for the lower specific speed conditions under which the upper runner operates, thus eliminating cavitation of the upper runner and permitting it to operate efficiently although this is done at the expense of limiting the output of the lower runner. The total specific speed of the prior units will, therefore, be the resultant of two identical runners each having a specific speed limited to suit the elevation of the upper runner. If the runners were identically designed to have a high specific speed in accordance with the elevation of the lower runner and thereby cause the lower runner to operate efficiently, then the runner would necessarily be unfit for operation at the elevation of the upper one due to cavitation and inefficiency of operation. Hence it is seen that if both runners are designed for the conditions of the lowermost runner the upper runner is subjected to prohibitive conditions while if both runners are designed for the conditions of the uppermost runner then the lower runner is subjected to unnecessary limitation of its power. Thus, these prior double runners have not combined in a single unit the feature of the highest possible specific speed along with proper operation of both runners as is made possible with my present invention.

I here present the principle that these disadvantages can be obviated, and that in a single turbine unit an upper runner may be used to increase the power, or for the same total power the actual speed of the unit may be increased, by applying runners of different form and capacity so that the upper runner will be of relatively less power and less specific speed and the lower runner of relatively greater power and greater specific speed, but both will be keyed to the same shaft and will run at the same actual speed.

Further objects of my invention in the form and cooperation of the turbine parts will appear from the following description taken in connection with the accompanying drawings, in which

Figure 1 is a vertical sectional elevation of a turbine unit embodying the invention, taken on line 1—1 of Figure 2;

Figure 2 is a horizontal sectional view on line 2—2 of Figure 1;

Figure 3 is a view similar to Figure 1 but illustrating a modification;

Figure 4 is a horizontal sectional view on line 4—4 of Figure 3;

Figure 5 is a view similar to Figure 1 but illustrating a modification.

Figure 6 is a horizontal sectional view on line 6—6 of Figure 5; and

Figures 7 and 8 are diagrammatic charts explanatory of the principles underlying the invention.

Figure 9 is a further modification of the runner combination.

In the embodiment of the invention shown in Figures 1 and 2 the flow from headwater enters the turbine through intake 10 in spiral form, passing the water with a whirl through fixed stay vanes 16 and adjustable guide vanes 17 to the transition space 17' between the upper runner 14 and the lower runner 15. The flow is guided into the two runners by the double conical distance piece or sleeve 30 and is discharged, usually with a whirl, upward into the draft tube 11 and downward into the draft tube 12, both of these tubes being of the annular spreading type adapted to convert the velocity head of both the meridian and tangential velocity components into pressure head. The draft tubes 11, 12 discharge through outlet passages 18 into tail water having its level indicated at t .

The runners 14, 15 are of the high specific speed propeller type, the upper runner 14 being smaller in diameter and of less power than the lower runner 15 and accordingly of lower specific speed than the lower runner. The unit shown is adapted to develop 9500 horsepower at 200 R. P. M. and a head of 40 feet. The throat of the lower runner is located 4' 9" below tail water so that the velocity head regained in the draft tube plus a factor to cover local cavitation, plus the static draft head will equal the barometric pressure corresponding to 32.83 feet water column. As thus installed the lower runner 15 will develop about 6000 of the total 9500 horsepower and its specific speed will be about 154. The upper runner 14 at the same actual speed will have a specific speed of about 118 and will develop approximately 3500 horsepower determined by the total draft head acting upon it at the throat, said draft head being computed as above indicated as the sum of the static draft head plus the velocity head regained in the draft tube, plus the factor to cover local cavitation. This total should not exceed 32.83 feet.

One of the principles underlying this in-

vention is thus the relation between the elevation of the turbine runner with respect to tail water, the effective head on the runner and its specific speed. As the design of a runner is progressively modified to increase its specific speed, the velocity head of the water passing through it continuously increases and represents an increasing fraction of the effective head. Assuming that the runner will be equipped with an efficient draft tube capable of regaining a large proportion of the velocity head discharged therefrom, the height at which the runner may be located with respect to tail water becomes more and more limited, requiring it to be placed at continually lower elevations, as the specific speed increases. In addition however to this allowance for velocity head based on the average velocity of the stream passing through the runner, a second factor must also be considered, namely, what I have termed "local cavitation," or local pressure reduction. The static pressure existing within the runner is not constant throughout the entire waterway but varies from the periphery toward the axis of the runner and also varies across each bucket from the face of one vane to the back of the next vane and there is therefore a local reduction of pressure at some points of the runner causing this local pressure to be a considerable amount below the average pressure in the entire waterway. This local pressure reduction may be expressed as the product of a coefficient multiplied by the effective head. This coefficient varies somewhat depending on the peculiarity of the individual runner design, but in general it increases with the specific speed of the runner, and for a runner of any given design characteristics, this coefficient must increase if the specific speed is increased.

A curve may be drawn showing the functional relation between this coefficient and the specific speed. Such a curve will represent the general effect of specific speed for runners of usual characteristics and show graphically how the coefficient of cavitation increases with an increase in specific speed. In designing any turbine installation, the specific speed selected for the runner must be such that at a given elevation of the runner with respect to tail water, the sum of the static elevation of the runner above tail water plus the amount of velocity head regained in the draft tube, plus the product of the cavitation coefficient k_c multiplied by the effective head must not exceed the barometric pressure head of the atmosphere.

It follows that if a runner of a given specific speed is placed too high above tail water so that the absolute pressure at a local point within the turbine approaches too close to the vapor pressure of water, the water may

part from the vane surfaces leaving a cavity filled with vapor, and at such points pitting or corrosion of the metal is likely to occur as well as vibration and a possible impairment of the power and efficiency.

If h_s is the elevation of the runner throat or point of minimum diameter of the turbine passage above tail water;

h_b , the barometric head corresponding to the temperature of the water and altitude of the location (corresponding to atmospheric pressure minus vapor pressure of the water);

H , the effective head on the turbine; and

N_s , the specific speed of the runner, then an approximate empirical relation may be found such that the absolute pressure at any local point within the turbine will not fall below the vapor pressure of the water for turbines of normal characteristics for various specific speeds.

From the available data representing the experience in existing plants, the effects of regained velocity head in the draft tube and the local pressure reduction within the turbine may be combined and expressed as a function of the specific speed. By this method, it is found that in order to provide a proper safeguard against cavitation a specific speed should be selected in relation to elevation above tail water and effective head in accordance with a formula of the following general form:

For turbines of the Francis type—

$$N_s \approx 125 \sqrt{\frac{h_b - h_s}{H}}$$

For turbines of the propeller type—

$$N_s \approx 150 \sqrt{\frac{h_b - h_s}{H}}$$

The coefficients of 125 and 150 are of course dependent upon the particular design characteristics, but the above round figures are sufficient for runners of usual design to provide a general guide in making preliminary calculations. In actual turbine design, the separate effects of cavitation and velocity head regain may be definitely calculated for the particular design and any necessary correction then made in the specific speed or elevation of runner above tailwater. Fig. 7 shows a chart representing this relation graphically, from which the specific speed can be selected in relation to elevation above tailwater and the head on the turbine for approximate or preliminary calculations. Aside from the exact value of the coefficient used, the formula will indicate the general nature of the functional relation between the above quantities. Fig. 7 is plotted with logarithmic coordinates, and the graphs are straight lines.

In a multi-runner vertical shaft turbine where the separate runners must be placed

at different elevations, the above formulas will serve as a basis for calculating the power capacity which can be safely assigned to each individual runner using in the case of each runner its own individual elevation h_s above tailwater. Since however the runners are all keyed to the same shaft and must therefore have the same absolute speed of rotation, the horsepower capacities will vary according to the following relation:

For Francis turbines—

$$HP = 15,600 \cdot \frac{H^{3/2}}{N^2} (h_b - h_s)$$

For propeller type turbines—

$$HP = 22,500 \cdot \frac{H^{3/2}}{N^2} (h_b - h_s)$$

in which N equals the revolutions per minute of the shaft.

The functional relations represented by these formulas are shown on Figure 8 in which the horsepower capacities of individual runners are plotted for a standard speed of 100 R. P. M. and for heads of 20, 40 and 60 feet in relation to the elevation of the individual runner with respect to tailwater. The horsepower for any other speed can be found by multiplying the horsepower at 100 R. P. M., denoted by (HP_{100N}) , by $\left(\frac{100}{N}\right)^2$, being the revolutions per minute.

It will be noted that the relation between the horsepowers of individual runners at constant speed and the runner elevations is a linear one, that is, if we take an elevation at a height above tailwater equal to the barometric head, which at ordinary temperatures and altitudes may be taken as approximately 32 feet, then the horsepowers of a series of runners at different elevations keyed to the same shaft will be very nearly proportional to their vertical distance below this 32 foot elevation when the runners are of the same general type. Therefore, all of the graphs plotted on this chart are straight lines radiating from a point at 32 feet elevation on the vertical axis of the chart. It will also be noted that a different slope of line must be used for turbines of Francis type from that required by the propeller type.

Therefore, the conditions in some cases will call for the lower runner of a multi-runner vertical shaft turbine to be of a different type from the upper runner. For example, in a turbine for 60 feet head, if the upper runner must be placed higher than about five feet above tailwater, the conditions for this upper runner would not be suitable for a propeller runner of usual characteristics according to present practice, and a Francis type runner would then be selected for the upper runner of such a unit. In a unit for such conditions, the lower runner, set at a lower elevation, could be of the propeller type and could there-

fore have a very much greater capacity than the upper runner.

If in the above formulas, the quantity $h_b - h_s$ is called the absolute static draft head, then it follows that the power capacities of a series of runners mounted on a common shaft should be approximately proportional to their individual absolute static draft heads when the runners are of similar type.

By thus combining with the lower runner the upper runner of less power and of lower specific speed, the power output is greatly increased and the same actual speed of rotation is maintained. In the example given (Figs. 1 and 2) the power is increased by over one-half to attain a total output of 9500 H. P. To attain this same horse-power in a single runner at the same head and same actual speed, the specific speed of the unit would be 193.5 and the runner should be placed about seventeen feet below tailwater in order to keep the total draft head of the unit equal to or less than 32.83. With this high specific speed a runner would be used that would develop a maximum efficiency considerably lower than the total efficiency of the combined unit of Figs. 1 and 2. The single runner unit, due to the high negative static draft head, would also require a much deeper excavation than the double unit. On the other hand, if the same specific speed were used for the single runner unit as in the lower runner of the unit shown, the actual speed would be materially reduced, the efficiency somewhat lower, and the size of the runner and of the whole unit considerably greater.

The new results of my invention are attained in the turbine of Figs. 1 and 2 simply by interposing the upper or auxiliary runner 14 on the shaft 21 between the lower runner 15 and the generator 22, and providing this runner with the supply and discharge passages for the flow through it. This involves simply a lengthening of the entrance guide vanes and the provision of the flow passage and discharge outlet passage for the upper runner. A continuous columnar support is provided from the sub-foundation to the generator floor by the stay vane rings 20, 16 and 19, and the shaft unit as a whole is made vertically removable and replaceable by forming the outer wall of the upper draft tube as a removable liner 29, setting in a cylindrical space of sufficient diameter to clear the larger periphery of the lower runner 15 as it is withdrawn upward. Thus the entire unit may be dismantled from above.

Due to the large overhang of the shaft 21 beyond the upper guide bearing 23 in removable draft tube cone 24, a lower guide bearing 25 is added in the lower draft tube cone 26, these bearings being supplied with lubricant through pipe connections 27 and 28.

The single ring of guide vanes 17 serving

for both runners is operated by submerged operating mechanism comprising ring 40 and links 41 between the ring and vanes, the ring being connected by reach rods 18 and rocker arm 43 to be turned by the vertical shaft 42 from power means controlled by the governor on the power house floor above.

In the embodiment of the invention shown in Figs. 3 and 4, the intake 31 is divided, having upper and lower sections 32 and 33, 75 directing the flow to the runners 34 and 35, mounted on vertical shaft 36. The section 32 directs the flow downwardly to the upper runner 34, through the downwardly flaring draft tube 37 to the common, single collector 38, and 80 the section 33 directs the flow upwardly to the lower runner 35, through the upwardly flaring draft tube 39 to the common, single collector 38. The flow from both sections of the intake passage flows upwardly and downwardly into common collector 38, passing out through passage 40^a to tail water. The liner of the downwardly flaring draft tube 37 is made removable so that the entire unit can be dismantled from above. Separate stay vanes 40^b and 41 in the sections 32 and 33 and separate stay vanes 42 in the collector 38 carry the vertical loads of the power house. Fixed diagonal guide vanes 43 and 44 direct the flow into the runners 34 and 35, causing the unit to run at maximum efficiency at all times. The load variations, however, can be taken up on some other unit in the power system so that this turbine of Figs. 3 and 4 is particularly advantageous in large interconnected 100 systems.

The two guide bearings 45 and 46 for the shaft 36 have independent water supplies 47 and 48 receiving their water from any convenient source.

In this turbine of Figs. 3 and 4, the installation has been worked up for a head of 40' and a speed of 200 R. P. M. The lower runner except for having the blades substantially entirely overlapping would be similar to that described in Fig. 1, developing 6000 horsepower and the throat placed at an elevation of 4.75' below tail water. The upper runner would develop 2000 horsepower at a specific speed of 89. The power of the upper runner has been worked out in this case by the method outlined above for Fig. 1, so that the total draft head at the runner throat will not exceed 32.83.

If a single runner unit were used in place of the two runners proposed, it would have 120 8000 horsepower, 40' head, 200 R. P. M., which corresponds to a specific speed of 177.5. This single runner unit would be placed with the throat of the runner about 12' below low 125 tail water. In this installation and likewise in that shown in Fig. 1, the single runner unit would require a considerably larger throat diameter than either of the runners in the two-runner unit. Due to the high specific 130

speed, the efficiency of this single unit would probably be 4% or 5% lower than the combined efficiency of the two runners. Or, if the same efficiency should be required, the speed would have to be materially reduced and the runner and other parts be made much larger than either of the two runners shown.

Since with a turbine of my invention one of the runners will be at a higher elevation than the other and usually above tailwater level, it may, in many instances, be advantageous to confine the regulation of the flow to the upper runner or runners, leaving the lowermost runner or runners to have a constant flow.

In Figs. 5 and 6, for instance, the vertical shaft turbine shown receives its flow through entrance passage 50 supplying the volute intakes 51 and 53 leading to upper runner 52 and lower runner 54 which pass the flow on into the draft tubes 55 and 56 respectively, discharging into the central draft chest 57 from which the discharge flow passes out through outlet passage 58 to tailwater having its level at t . A pier 58^a divides passage 58, it being noted that in Fig. 6 both runners and their openings are similarly offset with respect to the longitudinal center line of the complete passage 58.

The lower runner 54 is provided with fixed guide vanes 65 which serve at the same time as stay vanes to support the superimposed powerhouse structure, and this lower runner therefore has no regulating means. The lower part of the turbine is therefore of very simple construction, the only working parts being the runner and bearing 67 below the runner, thus avoiding any mechanism which will require attention in this relatively inaccessible location.

The upper runner is provided with wicket gates 63 with outside operating mechanism 66 in the turbine pit 68 where it is accessible. This unit therefore would be capable of governing for load changes up to about a third of the full capacity of the unit, which in most cases would be sufficient to take care of the usual load fluctuations occurring during normal operation. Below about two-thirds loads, it will be necessary to close the head gates and shut down the unit, the load then being taken up by other units in the station.

The draft chest 57 provides a clear opening for the withdrawal of the lower runner 54 upward by first removing the upper head cover 70, guide vanes 63, runner 52, lower distributor ring 69 and draft tube ring 62. The shaft 60 is divided into a separate section for each runner for convenience in handling, the intermediate coupling being provided with a nut guard 61 formed to suit the hydraulic flow.

In some cases, the lower runner 54 could be made in sections, each section being small

enough to permit its removal upward through the throat of the upperturbine without requiring the removal of a draft tube ring. The upper runner has separate cast stay vanes 64 set in the concrete outside of the guide vanes.

By my invention a multi-runner vertical shaft turbine is created which will have a considerably greater power and a total or combined specific speed than it is possible to secure by a single runner under given conditions of efficiency and security against cavitation. In general this unit will require for its lower runner a runner of higher specific speed than its upper runner and in some cases the specific speeds will be such that the lower runner will be of a high speed propeller type while the upper runner 75 will be of a lower specific speed Francis or mixed-flow type, as shown in Fig. 9. To accomplish this difference in specific speed between the upper and lower runners and also to obtain further advantages one or both of the runners, but preferably the upper runner, can be of the adjustable blade type such as shown in either of my copending applications Serial Nos. 553, 294 and 631,955, filed respectively April 15, 1922 and April 14, 1923. The invention is thus not limited to any particular type of runner and it is obvious that more than two runners may be used, and as shown in Fig. 9 and others the flow to the runners may be individually controlled as by any usual mechanism, such as wicket gates 76. Aside from the feature that both runners and their openings lie on the longitudinal central axis of the complete outlet 58 and are thereby symmetrically disposed with respect thereto, the remaining structure of Fig. 9 is similar to that shown in Fig. 5 and therefore the corresponding parts are given the same reference numbers. Since the actual speed of all runners must be the same to permit their being keyed to the same shaft, the lower specific speed of the upper runner necessarily requires that it shall have lower horsepower capacity and quantity of discharge than the lower one. The resulting combination produces a unit which is higher in the effective speed of the unit than can be produced either by a single runner or by a multi-runner unit having runners of identical size and design.

I claim:

1. In a hydraulic turbine the combination with a single shaft, of a plurality of runners thereon having different specific speeds and adapted for simultaneous normal operation.

2. In a hydraulic turbine the combination with a single shaft, of a plurality of runners thereon at different elevations and having different specific speeds while simultaneously normally operating.

3. In a hydraulic turbine the combination with a single shaft, of a plurality of runners spaced from each other on said shaft, said

runners having different power capacities and the same actual normal speeds at all times.

4. In a hydraulic turbine the combination with a single shaft, of a plurality of runners spaced from each other at different elevations on said shaft, said runners having different power capacities.

5. In a hydraulic turbine the combination with a single shaft, of a plurality of runners spaced from each other at different elevations on said shaft, said runners having different power capacities and different specific speeds.

6. In a hydraulic turbine the combination with a shaft, of a plurality of runners thereon at different elevations, an upper runner thereof having a lower specific speed than a lower runner thereof.

7. In a hydraulic turbine the combination with a shaft, of a plurality of runners thereon at different elevations, an upper runner thereof of having less discharge capacity than a lower runner thereof.

8. In a hydraulic turbine the combination with a shaft, of a plurality of runners thereon at different elevations, an upper runner thereof having a lower specific speed and less power capacity than a lower runner thereof.

9. In a hydraulic turbine, the combination with a single shaft, of a plurality of runners thereon having different specific speeds and adapted for simultaneous normal operation, the lower runner being below tailwater level and the upper runner above tailwater level.

10. In a hydraulic turbine the combination with a single shaft, of a lower runner driving said shaft and having during normal operation the full permissible speed corresponding to its elevation, and an upper runner on said shaft above said lower runner and having during normal operation the full permissible speed corresponding to its elevation, said permissible speeds being identical.

11. In a hydraulic turbine the combination with a shaft, of an upper runner of relatively less power capacity and lower specific speed, and a lower runner of relatively greater power capacity and relatively higher specific speed, said shaft and runners rotating at the full permissible speed of the lower runner.

12. In a hydraulic turbine the combination with a shaft, of a plurality of runners of similar type mounted thereon and having power capacities approximately proportional to their respective absolute static draft heads.

13. In a hydraulic turbine the combination with a shaft, of a plurality of runners thereon at different elevations, each of said runners having a specific speed and power capacity such that the sum of its static draft head plus the velocity head regained in its draft tube plus the factor to cover its local cavitation is less than 32.83 feet.

14. In a hydraulic turbine the combination

with a shaft, of a plurality of runners thereon at different elevations, each of said runners having a specific speed and power capacity such that the sum of its static draft head plus the velocity head regained in its draft tube plus the factor to cover its local cavitation approaches but does not exceed 32.83 feet.

15. In a hydraulic turbine the combination with a shaft, of an upper runner of relatively less power capacity and lower specific speed, and a lower runner of relatively greater power capacity and relatively higher specific speed, the speed of said shaft being such that for each of said runners the sum of its static draft head plus the velocity head regained in its draft tube plus the factor to cover its local cavitation approaches but does not exceed atmospheric pressure minus vapor pressure of the water.

16. In a hydraulic turbine, the combination with a single shaft, of a lower runner driving said shaft and having during normal operation the full permissible speed corresponding to its elevation, and an upper runner on said shaft above said lower runner and having during normal operation the full permissible speed corresponding to its elevation, said permissible speeds being identical, the lower runner below tailwater level and the upper runner above tailwater level.

17. In a hydraulic turbine, the combination with a single vertically disposed shaft, of a plurality of runners thereon having different specific speeds, one of said runners at a lower elevation having non-adjustable guiding means for the flow to it while an upper runner has adjustable means regulating the flow to it.

18. In a hydraulic turbine the combination with a shaft, of a plurality of runners mounted thereon in fixed relation to each other, non-adjustable guiding means for passing the flow to one of said runners and adjustable means for regulating the flow to another of said runners whereby said turbine is adapted to operate with a variable proportioning of the total flow between said runners.

19. In a hydraulic turbine the combination with a shaft, of a plurality of runners mounted thereon at different elevations in fixed relation to each other, non-adjustable guide means for passing the flow to one of said runners, and adjustable means for regulating the flow to another of said runners whereby said turbine is adapted to operate with a variable proportioning of the total flow between said runners.

20. In a hydraulic turbine the combination with a shaft, of a plurality of runners mounted thereon in fixed relation to each other, non-adjustable guide means for passing the flow to a lower runner, and adjustable means for regulating the flow to an upper

runner whereby said turbine is adapted to operate with a variable proportioning of the total flow between said runners.

21. In a hydraulic turbine the combination with a shaft, of a plurality of runners mounted thereon in fixed relation to each other, non-adjustable guide means for passing the flow to a runner below tailwater level and adjustable means for regulating the flow 10 to a runner above tailwater level whereby said turbine is adapted to operate with a variable proportioning of the total flow between said runners.

22. In a hydraulic turbine a divided intake 15 passage, a shaft, a runner on the end of said shaft receiving its flow upwardly, a second runner of different specific speed and power output than the first mentioned runner receiving its flow downwardly and spaced 20 therefrom, oppositely disposed draft tubes for said runners, and a common collector passage for receiving the discharge from both of said draft tubes.

23. In a hydraulic turbine a divided intake 25 passage, a vertical shaft, a runner on the lower end of said shaft receiving its flow upwardly, a second runner of different specific speed from the first mentioned runner mounted on said shaft and spaced from the 30 first mentioned runner, outwardly flaring draft tubes for said runners, and a central common collector passage receiving the flow from said draft tubes.

24. In a hydraulic turbine, an intake passage, a discharge passage, a vertical shaft, a plurality of runners of different specific speeds and output spaced from each other on said shaft, draft tubes for receiving the discharge from said runners, the upper draft 40 tube having removable portions to permit the complete dismantling of the entire turbine from above.

25. In a hydraulic turbine, an intake passage, a discharge passage, a vertical shaft, a plurality of runners of different specific speeds and output spaced from each other on said shaft, draft tubes for receiving the flow from said runners, the upper draft tube having removable liners to permit the complete 50 dismantling of the entire turbine from above.

26. In a hydraulic turbine, the combination with a shaft, of a plurality of runners thereon, means for conducting fluid to each of said runners, including fixed non-adjustable 55 means for directing fluid to certain of said runners, and means for controlling flow to another of said runners whereby flow to one of said runners can be stopped while continuing to the other of said runners.

27. In a hydraulic turbine, the combination with a vertical shaft, of a plurality of runners thereon spaced at different elevations, the power capacity of each runner being approximately proportional to its depth below 65 the barometric elevation above tail water.

28. In a hydraulic turbine, in combination, a vertical shaft having upper and lower runners, and means for regulating the power capacity of the upper runner and non-regulating power means for the lower runner. 70

29. In a hydraulic turbine, the combination comprising a plurality of runners set at different elevations and all rigidly fixed to a common shaft, a runner thereof at a higher elevation having less power capacity and 75 specific speed than a lower runner thereof, so that the power capacities and specific speeds of the runners will vary in different relation to their elevations with respect to the level of tailwater. 80

30. In a hydraulic turbine, the combination comprising a single vertically disposed shaft, and a plurality of runners thereon having different specific speeds and adapted for simultaneous normal operation, each of said 85 runners being of the propeller type. 85

31. In a hydraulic turbine, the combination comprising a single vertically disposed shaft, a plurality of propeller type runners thereon having different specific speeds and adapted 90 for simultaneous normal operation, and passage forming means whereby fluid flowing to each of said runners is turned from a radial to an axial direction. 95

32. In a hydraulic turbine, the combination 95 comprising a single vertically disposed shaft, a plurality of propeller type runners thereon having different specific speeds and adapted for simultaneous normal operation, passage forming means whereby fluid flowing to each 100 of said runners is turned from a radial to an axial direction, and guide vanes in said passages spaced from said runners to form a vane-free transition space. 100

33. In a hydraulic turbine, the combination comprising a single vertically disposed shaft, a plurality of runners thereon having different specific speeds and adapted for simultaneous normal operation, means forming 105 passages whereby the fluid is directed to said runners, and only fixed guide vanes in said passages. 110

34. In a hydraulic turbine, the combination comprising a single vertically disposed shaft, a plurality of propeller type runners thereon having different specific speeds and adapted for simultaneous normal operation, means forming passages leading to said runners, vanes disposed in each of the passages leading 115 to said runners, and additional vanes of the adjustable type disposed in the passage leading to one of said runners whereby the fluid flow may be variably controlled. 120

35. In a hydraulic turbine, the combination comprising a single vertically disposed shaft, 125 a plurality of propeller type runners thereon having different specific speeds and adapted for simultaneous normal operation, means forming passages leading to said runners, vanes disposed in each of the passages leading 130

to said runners, and additional vanes of the adjustable type disposed in the passage leading to one of said runners whereby the fluid flow may be variably controlled, said adjustable vanes being spaced from the runner with which they cooperate thereby forming a vane-free transition space.

36. In a hydraulic turbine, the combination comprising a single vertically disposed shaft, a plurality of runners thereon having different specific speeds and adapted for simultaneous normal operation, the upper runner being of the Francis type and the lower runner of the propeller type.

37. In a hydraulic turbine, the combination comprising a single vertically disposed shaft, a plurality of runners thereon having different specific speeds and adapted for simultaneous normal operation, the upper runner being of the Francis type and the lower runner being of the propeller type, means forming passages leading to said runners and adjustable guide vanes for the Francis runner disposed within the passage leading thereto.
